UNITED STATES PATENT OFFICE

ERNEST T. PEARSONS, OF LAKEWOOD, OHIO

DESIGN FOR A VEHICLE BODY

Application filed August 27, 1928. Serial No. 27,969. Term of patent 7 years.

To all whom it may concern:

Be it known that I, ERNEST T. PEARSONS, a citizen of the United States, residing at Lakewood, in the county of Cuyahoga, and State of Ohio, have invented a new, original, and ornamental Design for Vehicle Bodies, of which the following is a specification, reference being had to the accompanying drawing, forming part thereof.

Fig. 1 is a side elevation of a vehicle body showing my new design.

Fig. 2 is a rear elevational view.

In my new design, an unbroken belt of

molding extends across the rear side of the body and forwardly on the sides thereof. This belt is continued upwardly at an inclination and in spaced parallel relation to the upwardly inclined side of the rearmost window panel and then forwardly above and in spaced relation to the upper sides of the window panels.

I claim:

The ornamental design for a vehicle body, as shown and described.

ERNEST T. PEARSONS.
